To all whom it may concern:

Be it known that I, Leo Jiranek, a citizen of the United States and a resident of Scarsdale, county of Westchester, and State of New York, have invented a new, original, and ornamental Design for a Chair, of which the following is a specification, reference being had to the accompanying drawing, forming a part thereof, in which Fig. 1 is a perspective view of a chair, showing my new design. Fig. 5 is a rear perspective view of a chair embodying the design, on a scale smaller than that of Fig. 1.

I claim:

The ornamental design for a chair, substantially as shown.
